FLEXIBLE METALLIC TUBING.

973,238.

Specification of Letters Patent. Patented Oct. 18, 1910.

Application filed June 24, 1910. Serial No. 568,677.

To all whom it may concern:

Be it known that I, HENRY TIDEMAN, a resident of Menominee, in the county of Menominee and State of Michigan, have invented certain new and useful Improvements in Flexible Metallic Tubing, of which the following is a full, clear, and precise specification.

My invention relates to flexible metallic tubing or conduit adapted particularly in the electric art for receiving electrical conductors or in other arts for conducting fluids and gases.

My invention concerns particularly that class of tubing which comprises outer and inner spiral members where the coils of the outer member overlap and bridge the interstices between the coils of the inner member.

One of the salient objects of my invention is to provide improved stock having a cross-section which will enable the stock to be more readily handled and wound to form the inner and outer spirals of the tubing, the cross-sections of the stock for the inner and outer coils being such that they can be very readily drawn or rolled.

Another salient object is to provide a form of stock for the inner spiral member which will present a smooth and straight inner surface so that when the stock is wound into spiral form with the coils close together the tubing will have a substantially cylindrical inner surface which will not chafe wires or conductors drawn through the tubing and which will offer the least resistance to the flow of gases or fluids.

Another salient object is to provide an outer surface of the stock for the inner coil and an inner surface of the stock for the outer coil, which surfaces will coöperate when the coils are formed to lock the inner coils together and to form a tight connection between the inner coils, which connection, however, is yielding enough to allow the tubing to be readily bent, the arrangement being also such that the greater the bend of the tubing the greater will be the pressure between the outer and inner coils and the tighter will be the sealing connection between the inner coils. This feature eliminates the necessity of packing between the coils to prevent leakage when gases and fluids under pressure are conducted through the tubing.

The nature of my invention will be readily

understood by reference to the following specification and the accompanying drawings.

In these drawings Figure 1 is an elevation view of a length of tubing partly broken away and in section to more clearly illustrate the construction and arrangement and showing also a finish thimble arranged at one end of the tubing, and Fig. 2 is a similar view showing the arrangement when the tubing is bent.

The tubing comprises outer and inner spirals 1 and 2 of which the cross-sections are clearly indicated. The stock for the spirals can be readily rolled or drawn out like wire, the stock for the inner member having a straight, unbroken inner surface 3 and having along its outside edges the triangular ridges 4 and 5 forming between them the triangular median groove 6. When this stock is wound into spiral form the contiguous straight inner surfaces of the coils form a smooth, cylindrical inner surface for the tubing which offers the least resistance to the passage of electrical conductors through the tubing or to the flow of gases or fluids. The stock for the outer spiral has a median central triangular ridge 7 and the flanges 8 and 9 along the outer edge, triangular grooves or channels 10 and 11 being formed between the central ridge 7 and these edge flanges. The outer surface of the stock is rounded to be substantially semi cylindrical, as shown. After the inner spiral has been wound the outer spiral is wound about the periphery thereof, the grooves or channels 10 and 11 of the outer coils receiving the ridges 4 and 5 of adjacent inner coils, the ridges 7 of the outer coils engaging between the ridges of adjacent inner coils and the flanges 8 and 9 of the outer coils engaging the outer surfaces of the ridges of adjacent inner coils. The apex angle of the central ridge of the outer member may be the same as the angles of the ridges on the inner member, or may be greater, as shown. When the tubing is straight, as indicated in Fig. 1, the points of the ridges on the inner coils engage intimately in the apexes of the grooves 10 and 11 of the outer coils, and the inner surfaces of the flanges 8 and 9 engage intimately with the outer surfaces of the ridges 4 and 5 so that a tight and efficient sealing engagement results between the outer and inner

coils. If the tubing is used for conducting fluids under pressure the pressure will have a tendency to expand the inner coils more than the outer coils on account of the greater surface presented by the inner coils; and the result is that the greater the pressure the more intimately will the ridges on the inner coils be associated with the grooves and surfaces of the outer coils. In other words, increase in pressure within the tubing results in increase of sealing connection between the inner coils, and the necessity for additional packing or sealing material is, therefore, eliminated when the tubing is used for gases or fluids under pressure. Owing to the cylindrical inner surface presented by the inner spiral, end or finish thimbles 12 can be readily inserted without the necessity of special tools or apparatus. The inner surface 13 of the thimbles can be rounded and tapered inwardly, as shown, so as to prevent chafing of conductors when pulled through the tubing. This straight cylindrical inner surface of the tubing also enables tubing sections to be very readily coupled together with a tight fit.

If the tubing is designed to be bent, the inner spiral is wound to leave gaps 14 between the coils, so that when the tubing is bent the sections of the inner coils along the concave side of the bend will approach each other and the ends of the coils adjacent the convex side of the bend will separate, as indicated in Fig. 2. Upon such bending the outer coils will expand and the ends of the flanges 4 and 5 will leave the grooves or channels 10 and 11, the points of the flanges 4 and 5 along the concave side of the bend being brought more intimately into engagement with the faces of the central ridge 7, and the inner faces of the ridges 4 and 5 being pressed more intimately into engagement with the flanges 8 and 9. Efficient sealing between the coils will, therefore, in no way be diminished upon bending of the tubing, the sealing efficiency being in fact greater at the bend. When wires are drawn through tubing the greatest chafing will of course occur where the wires are drawn along bends. In my tubing, however, the surface over which the wires pass when drawn about a bend is smooth and contiguous and practically cylindrical, owing to the fact that the inner coils along the concave side of the bend engage to bring together the inner surfaces at this point, this forming the unbroken, substantially cylindrical surface 15 across which the wires drawn through the tubing can pass with the least friction. I, therefore, provide flexible tubing which can be very efficiently used for accommodating electrical or other conductors for gases and fluids, and which presents a cylindrical inner surface which offers the least resistance to the drawing through of

wires or to the flow of gases and fluids, and which tubing can be bent without increasing the friction and without diminishing the sealing efficiency between coils. Furthermore, the tubing comprises only two members which are so associated that efficient coupling and sealing conditions are maintained without the necessity of special packing or sealing material.

As changes and modifications are possible which would still come within the scope of my invention, I do not desire to be limited to the precise form and arrangement which I have shown, but

I desire to secure the following claims by Letters Patent:

1. In flexible tubing, the combination of an elastic metallic band having an exterior triangular ridge adjacent each longitudinal edge and wound into spiral form to form the interior member of the tubing, and a metallic band of elastic material having triangular grooves on its inner surface adjacent its longitudinal edges and wound spirally about the inner member and spanning adjacent coils of the inner member with its grooves receiving the triangular ridges of adjacent coils of the inner member to flexibly lock said inner coils together.

2. In flexible tubing, the combination of an elastic metallic band having an exterior triangular ridge adjacent each longitudinal edge and wound into spiral form to form the interior member of the tubing, and a metallic band of elastic material having triangular grooves on its inner surface adjacent its longitudinal edges and wound spirally about the inner member and spanning adjacent coils of the inner member with its grooves receiving the triangular ridges of adjacent coils of the inner member to flexibly lock said inner coils together, the inner surface of the band for the inner member being planar whereby when said band is wound into spiral form to form a substantially cylindrical interior surface for the tubing.

3. In flexible metallic tubing, the combination of an inner spiral member having exterior triangular longitudinal ridges, and an outer spiral member having interior longitudinal triangular grooves for receiving said triangular ridges to flexibly lock the coils of the inner member together.

4. In flexible metallic tubing, the combination of an inner spiral member having exterior triangular longitudinal ridges, and an outer spiral member having interior longitudinal triangular grooves for receiving said triangular ridges to flexibly lock the coils of the inner member together, the inner surfaces of the coils of the inner member forming a substantially continuous cylindrical inner surface for the tubing.

5. In flexible tubing, the combination of an inner spiral member formed of an elastic

metallic band having two triangular longitudinal ridges on its outer side, and an exterior spiral member formed of an elastic metallic band having two longitudinal triangular grooves on its inner side intimately receiving triangular ridges of adjacent coils of the inner spiral member.

6. In flexible tubing, the combination of an inner spiral member formed of an elastic metallic band having two triangular longitudinal ridges on its outer side, and an exterior spiral member formed of an elastic metallic band having two longitudinal triangular grooves on its inner side intimately receiving triangular ridges of adjacent coils of the inner spiral member, the inner surface of the band for the inner member being straight and the coils thereof being wound close together whereby a substantially unbroken cylindrical inner surface is formed for the tubing.

7. In flexible tubing, the combination of an inner spiral member formed of an elastic metallic bar having two triangular ridges on its outer side, and an outer spiral member formed from an elastic metallic bar having an inner triangular ridge on its inner side and two outer ridges on its inner side adjacent said inner ridge, such ridges forming between them triangular grooves, said grooves intimately receiving the triangular ridges of adjacent coils of the inner member and said triangular ridge of the outer member engaging between the triangular ridges of adjacent coils of the inner member. 25 30 35

In witness hereof, I hereunto subscribe my name this 25 day of March, A. D. 1910.

HENRY TIDEMAN.
